DESIGN FOR A COMBINED DISPLAY RACK AND ADVERTISING CARD

William Templin, Glen Ellyn, Ill.

Application February 13, 1933. Serial No. 47,194

Term of patent 3½ years

To all whom it may concern:

Be it known that I, WILLIAM TEMPLIN, a citizen of the United States, residing at Glen Ellyn, in the county of Du Page, and State of Illinois, have invented a new, original, and ornamental Design for a Combined Display Rack and Advertising Card, of which the following is a specification, reference being had to the accompanying drawing forming part thereof.

The figure is a perspective view of a combined display rack and advertising card showing my new design.

The article is particularly intended for displaying sample swatches or samples of goods for clothing.

I claim:

The ornamental design for a combined display rack and advertising card as shown and described.

WILLIAM TEMPLIN.
